UNITED STATES PATENT OFFICE

139,040

DESIGN FOR AN ELECTRIC IRON

William H. McLelland, Mansfield, Ohio, and Eric J. Ajax, Minneapolis, Minn., assignors to Industrial Tool & Die Works, Inc., Minneapolis, Minn., a corporation of Minnesota

Application May 17, 1944, Serial No. 113,630

Term of patent 14 years

(Cl. D49—6)

To all whom it may concern:

Be it known that we, William H. McLelland and Eric J. Ajax, citizens of the United States, residing, respectively, at Mansfield, county of Richland, State of Ohio, and Minneapolis, county of Hennepin, State of Minnesota, have invented a new, original, and ornamental Design for Electric Irons, of which the following is a specification, reference being had to the accompanying drawings, forming part thereof, and in which

Fig. 1 is a perspective view of the front, top and

one side of an electric iron showing our new design;

Fig. 2 is a top plan view thereof; and

Fig. 3 is a view of the side opposite that shown in Fig. 1.

We claim:

The ornamental design for an electric iron, substantially as shown.

WILLIAM H. MCLELLAND.
ERIC J. AJAX.
